UNITED STATES PATENT OFFICE.

LUCY MESSINA, OF WILMINGTON, DELAWARE.

DESIGN FOR A KNITTED FABRIC.

Application filed February 11, 1922. Serial No. 654. Term of patent 7 years.

To all whom it may concern:

Be it known that I, LUCY MESSINA, a subject of the King of Italy, residing at Wilmington, county of New Castle, State of Delaware, have invented a new, original, and ornamental Design for a Knitted Fabric, of which the following is a specification, reference being had to the accompanying drawing, forming part thereof.

The figure is a view in plan of a knitted fabric, showing my new design.

I claim:—

The ornamental design for a knitted fabric, as shown.

LUCY MESSINA.
